CLAIM

The ornamental design for a computer docking station, as shown.

DESCRIPTION

FIG. 1 is a perspective view taken from the top and right side of a computer docking station showing the new design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a rear and right side perspective view of the computer docking station.

The broken line showing both the laptop computer and the round button underneath the front dial is for illustrative purposes only and forms no part of the claimed design.

The dashed texture lines running along the lower half of the front of the docking station in FIGS. 1, 2 and 6 form part of the claimed design.
